UNITED STATES PATENT OFFICE

MELCHER G. WERME, OF WORCESTER, MASSACHUSETTS, ASSIGNOR TO WICKMIRE SPENCER STEEL COMPANY, OF NEW YORK, N. Y., A CORPORATION OF DELAWARE

FOLDING DISPLAY STAND

Application filed October 31, 1928. Serial No. 316,187.

This invention relates to a folding wire stand or rack on which package goods may be conveniently displayed.

It is the general object of my invention 5 to provide a stand or rack so designed that it will be strong and rigid when in use and that it may be conveniently folded to relatively small compass when not in use.

A further object of the invention is to 10 provide a rack which may be cheaply manufactured and easily assembled and which may be shifted from open to closed position or vice versa with a very slight expenditure of time and labor.

15 My invention further relates to arrangements and combinations of parts which will be hereinafter described and more particularly pointed out in the appended claims.

A preferred form of the invention is shown 20 in the drawings in which

Fig. 1 is a perspective view of my improved display rack;

Fig. 2 is an end elevation thereof;

25 Fig. 3 is a similar view, showing the stand folded; and

Figs. 4 and 5 are end views of detail parts.

Referring to the drawings, my improved 30 display stand comprises a pair of rigid side members, each side member having end posts or uprights 10 and 11, and upper and lower side bars 12 and 13, all firmly secured together preferably by electric welding. Arched braces 14 are welded at their lower ends to the end posts 10 and 11 and at their 35 middle portions to the lower side bars 13. The two side members are preferably identical in construction.

Spacing members 15 (Fig. 5) are provided, each spacing member having an eye 40 16 at one end and a hook 17 at the opposite end. The eyes 16 are closed around the upper and lower side bars 12 and 13 of one of the side members, and the hooks 17 are adapted to fit snugly over the upper and lower side bars 12 and 13 of the second side member. When the spacing members 15 are in operative position, the side members are held in predetermined spaced relation.

50 Upper and lower shelves are provided in my improved display stand, these shelves

being identical and each being formed of two members 20 and 21. The member 20 of each shelf comprises longitudinal rods 22 and 23 and cross rods 24, all of these parts being preferably welded together.

The cross rods 24 have eyes 25 (Fig. 4) 55 at one end, adapted to be closed around one of the upper side bars 12 previously described, so that the upper shelf member 20 swings freely about one of the side bars 12, while 60 the corresponding member 20 of the lower shelf swings freely about one of the lower side bars 13.

Each shelf member 21 also comprises longitudinally extending rods 30 and cross rods 65 32. The rods 32 have eyes 33 at their lower ends, closed around the longitudinal rod 23 of the associated shelf member 20. At their upper ends, the cross rods 32 have eyes 34 closed around one of the side bars 12 or 13. 70 As previously stated, the upper or lower shelves are practically identical in construction.

In order to prevent swaying of the stand 75 when in operative position, I have provided sway braces 40, each of which is provided with an eye at its upper end, closed around the longitudinal rod 23 of the upper shelf member 20.

The lower end of each sway brace is offset 80 laterally and bent in a horizontal place to form an eye 41, loosely slidably on the lower portions of the end posts 10 and 11.

As the parts of the stand are moved from 85 the position shown in Fig. 3 to that shown in Fig. 2, the upper and lower shelves are opened out to operative position and the longitudinally extending rods 23 thereof are correspondingly moved upward, the upper rod 23 sliding the eyes 41 of the sway braces 40 90 upward along the end posts 10 and 11.

As the parts of the stand reach their full 95 open position, the eyes 41 are drawn snugly against the lower side bars 13, preventing further upward movement thereof and adapting them to firmly resist swaying movement of the stand in either direction.

When the stand is opened up, it is merely necessary to snap the spacing members or hooks 15 into position and the stand is then 100

ready for use and will firmly support any package goods or other articles placed thereon.

When the stand is to be folded, it is only necessary to disconnect the spacing members 15 and swing them about their pivot rods 12 and 13 to a depending position along side the end posts 10 and 11. The side members may then be pushed directly toward each other, collapsing the stand as shown in Fig. 3.

Having thus described my invention and the advantages thereof, I do not wish to be limited to the details herein disclosed, otherwise than as set forth in the claims, but what

15 I claim is:—

1. A folding display stand comprising rigid side members, upper and lower shelves each formed in two parts, said parts being permanently hinged together along adjacent side edges and being permanently hinged along their opposite outer edges to said side members, detachable spacing members effective, when operatively connected, to hold said side members at a predetermined distance apart and when disconnected permitting a direct movement of approach of said side members toward each other, and means to prevent upward movement of the hinged center portions of said shelves when in operative position.

2. A folding display stand comprising rigid side members, upper and lower shelves each formed in two parts, said parts being hinged together and to said side members, 35 spacing members effective, when operatively connected, to hold said side members at a predetermined distance apart, and sway braces connecting the center hinged portion of said upper shelf to the lower parts of said side 40 members.

3. A folding display stand comprising rigid side members, upper and lower shelves each formed in two parts, said parts being hinged together and to said side members, spacing members effective, when operatively connected, to hold said side members at a predetermined distance apart, and sway braces connecting said upper shelf to the lower part of said side members, the lower ends of said sway braces being vertically slidable on said side members and said side members having means thereon to limit upward vertical movement of said sway brace ends.

4. A folding display stand comprising
55 rigid side members each having end posts and
upper and lower side bars, shelves each
formed in two parts, one of said parts being
permanently hinged at one edge to one of said
side bars and having a longitudinally extend-
60 ed rod at its opposite edge, the other part
being permanently hinged at one edge to the
corresponding side bar of the other side
member and being permanently hinged at its
opposite edge to said longitudinally extend-
65 ed rod, detachable means to hold said side

members in spaced relation, and means to prevent swaying of said stand, said side members being foldable by a movement directly toward each other when said holding means is detached, and said shelves remaining connected to both side members during such folding movement.

5. The combination in a folding display stand as set forth in claim 4, in which said means to prevent swaying comprises braces pivoted at their upper ends to said longitudinally extended rod and having offset horizontally disposed eyes at their lower ends 75
slidable on said side members below the lower side bars thereof. 80

6. The combination in a folding display stand as set forth in claim 4, in which said means to prevent swaying comprises braces pivoted at their upper ends to said longitudinally extended rod and having offset horizontally disposed eyes at their lower ends slideable on said side members below the lower side bars thereof, said sway braces being of such length that they engage said side bars and are limited in upward movement thereby when said stand is opened to operative position. 85 90

In testimony whereof I have hereunto affixed my signature.
